ROTARY CORE DRILL

John H. Howard, Huntington Park, Calif.

Application October 14, 1935, Serial No. 44,884

3 Claims. (Cl. 255—72)

This invention relates to a well tool and relates more particularly to a well drill capable of obtaining a sample or core of the earth formation. A general object of this invention is to provide 5 a simple, practical and improved rotary core taking well drill.

Another object of this invention is to provide a rotary well drill embodying a core barrel having a cutting head and adapted to be fed into 10 the earth formation to cut and receive a core of the formation and then be withdrawn from the well to permit the core to be examined without removing the outer barrel or drill proper.

Another object of this invention is to provide 15 a well drill of the character mentioned in which the core barrel may be fed into the earth formation in advance of the head of the drill and rotated with the drill to obtain a core of the formation and then removed from the well with the 20 core contained therein without enlarging the bore it has formed, thus leaving a reduced bore or rat-hole. The operation of the core barrel in advance of the drill head to form a reduced bore and the subsequent removal of the core 25 barrel without enlarging the reduced bore are important and facilitate the testing of the well as a suitable well tester may be run into the rat-hole or reduced bore following the examination of the core obtained without the necessity of 30 running a special drill into the well to form a rat-hole to receive the tester.

Another object of this invention is to provide 35 a sample taking drill of the character mentioned in which the core barrel is fed downwardly into the formation in advance of the outer barrel by hydraulic pressure or fluid pressure.

Another object of this invention is to provide 40 a well drill of the character mentioned that embodies a simple positive and effective means for transmitting rotation from the outer barrel to the fluid pressure actuated core barrel during the drilling and core cutting operation.

Another object of this invention is to provide 45 a drill of the character mentioned that includes means for informing the driller that the core barrel has reached the lower end of its downward stroke and, therefore, has received a core of sufficient length.

50 A further object of this invention is to provide a core taking well drill of the character mentioned that embodies a minimum number of simple sturdy parts and that is inexpensive of manufacture.

The various objects and features of my in-

vention will be fully understood from the following detailed description of a typical preferred form and application of my invention, throughout which description reference is made to the accompanying drawing, in which:

Fig. 1 is a central longitudinal detailed sectional view of the drill provided by this invention illustrating the core barrel in the operative position. Figs. 2, 3 and 4 are transverse detailed sectional views taken as indicated by lines 2—2, 10 5 3—3 and 4—4, respectively on Fig. 1.

The well drill of the present invention includes, generally, an outer barrel 10 having a cutting head 11 on its lower end, a core barrel 12 adapted to be run into the outer barrel 10, 15 and means 13 for feeding or advancing the core barrel 12 into the earth formation to obtain a core.

The outer barrel 10 constitutes the body of the 20 drill and is a tubular structure adapted to be connected with the lower end of a drilling string. In the particular form of the invention illustrated in the drawing the outer barrel 10 is sectional comprising an upper tubular section 14 and a lower tubular section 15. Means is provided at 25 the upper end of the upper section 14 for facilitating the connection of the drill with the drilling string. This means may take the form of a threaded socket 16 for receiving a threaded pin on the lower end of the string. A suitable threaded pin and socket connection 17 is provided 30 to connect the two sections 14 and 15 of the barrel 10. A threaded pin 18 is provided on the lower end of the section 15 to carry the cutting head 11. In accordance with the invention any 35 suitable form or type of cutting head may be provided on the barrel 10. In the drawing there is shown a typical cutting head comprising a tubular shoe 19 threaded on the pin 18 and spaced cutting parts 20 on the shoe. The cutting parts 20 are in the form of blades projecting 40 downwardly and outwardly from the lower end of the shoe 19 for making an annular cut in the earth formation. The blades 20 project inwardly at the lower end of the shoe 19 and are operable to make an annular cut of substantial 45 radial width or extent. During the drilling operation circulation fluid passes downwardly through the longitudinal opening 21 of the barrel 10 to discharge from the cutting head 11. 50 The opening 21 is comparatively large in diameter to receive the core barrel 12 and parts are provided on its wall to cooperate with the core barrel as will be hereinafter described.

The core barrel 12 is an elongate tubular mem- 55

ber adapted to be dropped or lowered through the drilling string to pass into the outer barrel 10 and may be fed downwardly by the means 13 to cut into the formation in advance of the 5 cutting head 11 and receive a core. The core barrel 12 is comparatively long and is adapted to fit in the opening 21 of the outer barrel 10 with substantial clearance leaving a fluid passage P. The longitudinal opening 22 of the barrel 12 is 10 open at its lower end and is adapted to receive the core of the earth formation as the barrel is rotated and fed downwardly into the earth formation. In accordance with the invention a cutting head 23 is provided on the lower end of 15 the core barrel 12. The cutting head 23 is proportioned to pass downwardly through the outer barrel 10 and to pass between the blades 20 of the cutting head 11, and is operable to make an annular cut and leave a core of the earth formation 20 for reception by the core barrel 12. The cutting head 23 includes cutting parts 24 in the form of downwardly projecting cutting blades arranged in an annular series to make an annular cut when the barrel 12 is rotated and fed downwardly. A 25 core catcher 25 is provided to retain and support the core in the core barrel 12. The particular core catcher 25 illustrated in the drawing is a more or less typical form of core catcher rotatably supported in the cutting head 23 and embodying upwardly and inwardly projecting spring 30 fingers 26.

A valve is provided on the upper end of the core barrel 12 to prevent the circulation fluid from washing downwardly through the core barrel 35 and to permit the discharge of fluid from the core barrel as it is displaced by the entering core. The valve may include a connector or adapter 27 threaded into a socket 28 in the upper end of the core barrel 12 and carrying a transverse or 40 horizontal web 29. The web 29 has a central vertical port 30 which is controlled by a downwardly seating valve or ball 31. An upstanding rim 32 is provided on the web 29 around the port 30 to assist in retaining the ball 31 against displacement. A member 33 projects upwardly from the adapter 27 and has a valve chamber 34 receiving the rim 32 and confining the movable ball 31. Ports 35 connect the chamber 34 with the passage P to permit the discharge of fluid 45 from the interior of the core barrel 12 when the valve or ball 31 is open.

The invention provides a novel releasable drive for transmitting rotation from the outer barrel 10 to the core barrel 12. This drive is such that 50 it is automatically engaged when the core barrel 12 is dropped or run into the outer barrel 10. The rotation transmitting drive includes a plurality of spaced longitudinal splines 36 on the wall of the openings 21 and a plurality of spaced longitudinal splines 37 on the core barrel 12 for 55 cooperating with the splines 36. The splines 36 are preferably on the interior of the lower barrel section 15. When in engagement the splines 36 and 37 form a positive rotative drive between the outer barrel 10 and the core barrel 12.

Novel and particularly effective means is provided for guiding or directing the splines 37 of the core barrel 12 between the splines 36 when the core barrel is dropped or run into the outer 60 barrel 10. A plurality of circumferentially spaced lugs 38 is provided on the wall of the opening 21. The lugs 38 are spaced above the upper ends of the splines 36 and are in vertical or longitudinal alignment with the splines. The upper 65 ends of the lugs 38 are pitched or inclined up-

wardly and inwardly to central upwardly facing edges. The lower ends of the splines 37 may be similarly formed and when the core barrel 12 is lowered or run into the outer barrel 10 the lower ends of the splines 37 engage the pitched ends 5 of the lugs 38 and this cooperation causes the core barrel 12 to turn to a position where its splines 37 are free to pass downwardly between the splines 36. The splines 37 are thus engaged with the splines 36 without excessive shock to 10 the parts. The splines 36 and 37 are formed and related to centralize the core barrel 12 in the outer barrel 10 and to permit the free downward feeding or movement of the core barrel 12 relative to the outer barrel 10. The spaces between 15 the spaced splines 37 constitute continuations of the passage P, as illustrated in Fig. 4, when the core barrel 12 is in the operative position within the outer barrel 10. The lugs 38 spaced upwardly from the splines 36 may assist in guiding 20 and centering the core barrel 12.

The means 13 for advancing or feeding the core barrel 12 into the earth formation is a feature of the invention as it provides for the advancement of the core barrel 12 relative to the 25 outer barrel 10 during rotation of the drill to move the cutting head 23 downwardly in advance of the cutting head 11 so that the barrel 12 receives a core of the formation in advance 30 of the cutting head 11. The feeding or advancing means 13 is in the nature of an hydraulic 35 means or fluid pressure means and is under the full control of the driller. In accordance with the invention the means 13 includes a piston or plunger on the upper end of the core barrel 12 operating in the opening 21 of the barrel 10. The plunger comprises a sealing element 40 surrounding the upper end portion of the member 33 and bearing downwardly against an annular flange 41 on the member. A head or nut 42 is 40 threaded on the upper end portion of the member 33 to clamp or retain the sealing element 40 in position. The sealing element 40 is shaped and proportioned to effectively seal outwardly against the wall of the opening 21 under the action 45 of downward fluid pressure.

Means is provided for producing a differential or drop in pressure at the opposite sides of the sealing element 40 so that the pressure on the circulation fluid pumped through the drilling 50 string feeds or forces the core barrel 12 downwardly. The member 33 has a fluid chamber 43 below the flange 41 and spaced ports 44 extending upwardly from the chamber 43 to its upper end. Ports 45 in the wall of the member 33 connect the chamber 43 with the fluid passage P. Orifice members or chokes 46 having small ports or passages 47 are provided in the upper portions of the ports 44. The chokes 46 operate to materially restrict the flow downwardly through the 60 ports 44 to provide for a substantial drop in fluid pressure at the lower side of the sealing element 40 so that the circulation fluid under pressure pumped downwardly through the string acts on the sealing element 40, the nut 42 and the upper 65 end of the member 33 to force or feed the core barrel 12 downwardly relative to the outer barrel 10. A stem 48 is provided on the upper end of the member 33 to facilitate the handling of the core barrel 12 by a line provided with an over-shot or other device for engaging the stem. The 70 upwardly projecting stem 48 is provided with a tapered head 49 readily engageable by an over-shot or similar fishing tool.

In accordance with the invention the drill is 75

constructed to automatically signal to the driller that the core barrel 12 has received a sufficient amount of core. During the core receiving operation the fluid pressure acting on the sealing element 40, the nut 42 and the upper end of the member 33 feeds the core barrel 12 downwardly more rapidly than the outer barrel 10 is advanced, moving the head 23 downwardly into the earth formation in advance of the head 11. The lower side of the flange 41 is adapted to cooperate with the upper ends of the lugs 38 to limit the downward travel of the core barrel 12 relative to the outer barrel 10. The parts are proportioned and related so that the inner sides 15 of the lugs 38 directly oppose and close or substantially close the ports 45 when the lower side of the flange 41 cooperates with the upper sides of the lugs 38. Thus the downward flow of the circulation fluid is stopped or materially retarded 20 simultaneously with the stopping of downward movement of the core barrel 12 relative to the outer barrel 10. The restriction or closing of the ports 45 by the lugs 38 causes the pump or pumps delivering the circulation fluid to the 25 drilling string to labor, indicating to or informing the driller that the core barrel 12 has reached the lower end of its downward stroke and has received a sufficient core.

In operation the outer barrel 10 is connected 30 with the lower end of a well drilling string and run into the well for operation in accordance with the rotary method of well drilling. When it is desired to obtain a sample or core of the earth formation to determine its character the 35 core barrel 12 is dropped or run through the drilling string on a cable to land or come to rest in the outer barrel 10. As the core barrel 12 moves downwardly through the outer barrel 10 the lower ends of the splines 37 contact or engage the tapered upper ends of the lugs 38. The 40 taper of the lugs 38 causes the core barrel 12 to turn to a rotative position where its splines 37 may pass down between the splines 36 on the wall of the opening 21. Thus the splines 36 and 37 are engaged to form a positive rotative 45 drive between the outer barrel 10 and the core barrel 12.

Rotation of the drilling string is then resumed and the circulation fluid is pumped downwardly 50 through the drilling string to pass through the chokes 46, the ports 44, the chamber 43, the ports 45 and flow out through the passage P. The chokes 47 provide for a substantial drop in the pressure on the fluid below the sealing element 40 so that the pressure acting on the sealing element, the nut 42 and the upper end of the member 33 urges or feeds the core barrel 12 downwardly. Thus the core barrel 12 is fed 55 downwardly relative to the outer barrel 10 and is rotated with the outer barrel so that its cutting head 23 cuts into the earth formation. The hydraulic pressure acting downwardly on the core barrel 12 causes the cutting head 23 to drill into the formation in advance of the cutting head 11. The cutting head 23 fed downwardly in advance of the cutting head 11 forms a reduced bore 60 in the lower end of the well and leaves a core which is received in the core barrel 12. As the core is received in the core barrel 12 the fluid trapped in the core barrel is displaced through the port 30, the chamber 34 and the ports 35.

The drilling or coring operation is continued 65 until the core barrel 12 is fed downwardly relative to the outer barrel 10 to a point where the lower end of the flange 41 contacts the lugs 38

This contact of course limits downward movement of the core barrel 12. When the flange 41 is in engagement with the lugs 38 the lugs oppose the ports 45 to close or restrict the ports. This stops or reduces the downward flow through 5 the drilling string and causes the pumps forcing the fluid through the string to labor. The laboring of the pump or pumps indicates to the driller that the core barrel 12 has reached the lower end of its stroke and has obtained a core of sufficient length. When the pump or pumps labor the driller discontinues the rotation and downward feed of the drilling string and prepares to remove the core barrel 12. A cable carrying an overshot or the like is run into the drilling string 10 and the overshot or fishing tool is engaged with the stem 48 to remove the core barrel. The line or cable is raised to pull the core barrel 12 upwardly out of the outer barrel 10 and upwardly through the drilling string. When the core barrel 12 is moved upwardly the core catcher 25 grips and holds the core to retain it in the core barrel. Thus the core is retained in the core barrel 12 and may be examined when the core barrel has been brought to the surface of the ground. 20 25

The withdrawal of the core barrel 12 as just described leaves a reduced bore or rat-hole in the lower end of the well. If the sample or core obtained in the core barrel indicates that it is desirable to make a test of the formation a well 30 tester may be run into the well to pass or extend into the reduced bore formed by the cutting head 23 of the core barrel 12. The drill involving the core barrel 12 fed into the formation in advance of the principal cutter 11 and removable from 35 the well without enlarging the reduced bore it has formed conditions the well for testing by a well tester without further drilling. If the character of the core obtained is such that it is not deemed advisable to test the formation the drill 40 may be continued with the drill and cores may be taken from time to time by means of the core barrel 12. The present invention provides a rotary well drill involving a core taking means that is positively rotated with the drill 45 and that is fed into the formation in advance of the principal cutter by hydraulic pressure to obtain a core and to leave a reduced bore or rat-hole. The tool is easy to control and operate and involves a minimum number of sturdy parts. 50

Having described only a typical preferred form and application of my invention I do not wish to be limited or restricted to the specific details herein set forth, but wish to reserve to myself any variations or modifications that may appear 55 to those skilled in the art or fall within the scope of the following claims:

Having described my invention, I claim:

1. A rotary well drill including a tubular body adapted to be operated on a tubular drilling 60 string, a tubular cutting head on the lower end of the body, a core barrel adapted to be passed through the string to the interior of the body, means for transmitting rotation from the body to the core barrel, a cutter on the core barrel 65 operable to cut a core for reception by the core barrel, means for feeding the core barrel downwardly to cause its cutter to cut a core in advance of the cutting head, and means for audibly signaling to the driller when the core barrel has 70 been advanced a predetermined extent.

2. In a rotary well drill construction, a barrel adapted to be operated on the lower end of a tubular drilling string, longitudinal splines on the interior of the barrel, a core receiving barrel 75

- adapted to be passed through the string into the barrel, splines on the core receiving barrel adapted to slidably cooperate with the splines on the barrel, lugs on the barrel for guiding the splines of the core barrel between the splines of the barrel, and a plunger carried by the core barrel for operating in the barrel, a head on the core barrel having a port establishing communication between the string and the interior of the barrel 10 and effecting a drop in pressure below the plunger whereby the fluid pumped through the string acts on the plunger to feed the core barrel downwardly, one of the lugs substantially closing the port when the core barrel has been fed 15 a predetermined distance.
3. In a rotary well drill construction, a barrel adapted to be operated on the lower end of a tubular drilling string, a cutter head on the lower

end of the barrel, a core barrel adapted to be passed through the string into the barrel, parts on the barrel and core barrel adapted to cooperate to transmit rotation and allow longitudinal movement of the core barrel in the barrel, there being a longitudinal fluid passage between the barrel and core barrel, a plunger on the core barrel operable in the barrel, there being a port in the core barrel establishing communication between the string and the passage and effecting a drop in pressure below the plunger whereby fluid pumped through the string feeds the core barrel downwardly relative to the barrel, and a part on the barrel adapted to restrict the flow through the port when the core barrel has been 15 fed downwardly a predetermined extent.

JOHN H. HOWARD.
